The ornamental design for modular backdrop system duo connectors, as shown and described.

DESCRIPTION

FIG. 1 is a top perspective view of the modular backdrop system duo connectors of the instant invention.

FIG. 2 is a bottom perspective view thereof.

FIG. 3 is a front view thereof.

FIG. 4 is a rear view thereof.

FIG. 5 is a top view thereof.

FIG. 6 is a bottom view thereof.

FIG. 7 is a left side view thereof; and,

FIG. 8 is a right side view thereof.

The dashed broken lines depict portions of the modular backdrop system duo connectors that form no part thereof. The broken lines in FIG. 7 depict hidden portions of the modular backdrop system duo connectors.
